ATHLETIC EQUIPMENT CARRIER RACK

Melvin W. Potts, Roff, Okla.

Application March 12, 1956, Serial No. 40,539

Term of patent 14 years

(Cl. D14—3)

Fig. 1

Fig. 2

Fig. 3

Fig. 1 is a front perspective view of an athletic equipment carrier rack embodying my new design;
 Fig. 2 is a rear perspective view thereof; and
 Fig. 3 is a detail sectional view on the line 3—3 of Fig. 2.

The portions shown in broken lines are for purposes of illustration only.

What I claim is:

The ornamental design for an athletic equipment carrier rack, as shown and described.
